WINDOW SQUEEGEE

Nykyfor Hawrylasz, Minneapolis, Minn.

Application June 30, 1933, Serial No. 678,458

7 Claims. (Cl. 15—245)

My invention is for a window squeegee having replaceable parts which are connected together to form a unitary structure. The holder for the flexible squeegee strip is a channel-shaped member, and is removably attached to the handle which is formed with a socket to receive a stick. The channel member is adapted to hold the squeegee member which is in the form of a strip of flexible material, adjustable and replaceable, so that the same may be adjusted by reversing it which permits the use of all of the edges thereof. When the squeegee member becomes worn on one edge it may be reversed in the holder, thereby giving a greater utility to my window squeegee. Further, the flexible squeegee member may be replaced when it is finally worn out, by a new member of a similar character.

It is a feature to provide a simple, inexpensive unitary holder for the squeegeeing strips, one of which acts as the flexible wiping member and which is adapted to contact the glass, while the other is a flexible reinforcing member and is spaced from the marginal working edge of the squeegee member. A further feature resides in providing a means of reinforcing the rubber squeegee member to provide a firmer nature to the body of the same, yet leaving the working edge thereof free to flex in operation. Thus a better squeegee is provided because the squeegee member may be made of a softer material, such as flexible rubber and yet the body may be caused to be firm enough to support the edge of the squeegee member so that it will clean the window over which it is drawn in use.

A feature resides in means for retarding the flow of water along the under edge of the squeegee member while operating to clean a surface. The squeegee member is provided with openings or wells into which the water or liquid wiped from a surface being squeegeed is adapted to collect, thus retarding the flow of the same and preventing the water from dripping off the ends of the squeegee as it is carried across the glass to clean the same.

It is also a feature to provide the channel squeegee holding member with suitable clamping means which is adapted to removably support the squeegee member thereto and to also provide means for holding the body of the squeegee strip firm and in perfect alignment, which insures a true working edge for the squeegee.

The details and further features of my squeegee will be more fully set forth, wherein the replaceable and adjustable members may be con-

nected together to form a complete unitary squeegee adapted to have the advantage of giving longer wear and better efficiency in use than has been accomplished heretofore insofar as I know, and maintaining a simplicity of construction to make the same desirable.

In the drawing forming part of this specification:

Figure 1 is a plan view of my window squeegee.

Figure 2 is an under view showing a reverse side to that shown in Figure 1.

Figure 3 is an end view of the same.

Figure 4 is an enlarged section on the line 4—4 of Figure 2.

Figure 5 is a similar section to Figure 4, on the line 5—5 of Figure 2.

Figure 6 illustrates the flexible squeegee member.

Figure 7 illustrates the flexible squeegee back ing member.

Figure 8 is an enlarged section of an alternative construction of my window squeegee, indicating a section at a point similar to that of Figure 4.

My window squeegee A includes the supporting member B which may be formed channel shape or angular. In the channel shape the supporting member B has a wide flange 10 and a short flange 11, while a recess 12 is formed between the flanges 10 and 11. A handle member C which is formed with a socket 14 for receiving a stick is secured to the supporting member B by the screws 15. The handle C may be replaced or removed by loosening the screws 15 when it is desired.

The squeegee strip 16 is formed of a width so that it may be lined up in the channel recess 12 with the working edge 17 projecting beyond the width of the flange 10. This strip may be made of flexible material of any suitable nature, such as rubber or other material which will provide a firm yet soft, sharp squeegee edge 17. The squeegee strip 16 is formed with four sharp edges 17, each of which may be brought into position to provide the working surface of the squeegee A by resetting of the squeegee strip 16 in the supporting member B.

The squeegee strip 16 is provided with a series of holes 18 which are marginally spaced from one of the working edges 17, while a similar series of holes 19 are marginally spaced from the opposite working edge 17, as illustrated in Figure 6, so that the series of holes 18 and 19 provide parallelly spaced holes from the edges 17 of the strip 16. The holes 18 and 19 may be

equally spaced from the working edges 17, the purpose of which will be more fully hereinafter set forth.

I provide a backing strip 20 of rubber or other flexible material which is adapted to co-operate with the squeegee strip 16. The strip 20 is provided with holes 21, the purpose of which will be later set forth.

The squeegee strip 16 and the backing strip 20 are adapted to be placed in the supporting member B as illustrated in Figure 4, with one of their edges aligned in the channel recess 12. This gives a perfect alignment to the working edge 17 and holds the member 20 in a manner to 15 form a flexible reinforced backing means for the squeegee strip 16.

The strips 16 and 20 are adapted to be clamped in the supporting member B by means of a series of adjusting screws 22 which extend through 20 either the series of openings 18 or the openings 19 in the strip 16 and through the openings 21 in the strip 20, and engage the clamping bar 23 to hold the same with more or less tension against the members 16 and 20 to clamp the same firmly 25 to the supporting member B. This provides a unitary structure to the squeegee A, as illustrated in Figures 1 and 2, and the sections 4 and 5.

The clamping bar 23 may be made of any suitable width and shape to engage the squeegee 30 members. The squeegee strip 16 which is formed with the sharp edges 17 is reversible in the supporting member B so that any one of the edges may be brought into operative position. Thus as one of the working edges 17 wears, the position 35 of the strip 16 may be changed by loosening the screws 15 and 22, all of which would extend through the members 16 and 20, and are anchored in the bar 23. In this manner I provide a squeegee member 16 which is selectively positioned in 40 the supporting member B. It will be apparent that the series of holes 18 and the parallelly disposed series of holes 19 provide the adjustment of the strip 16 so that the same may be reversed in position in the supporting member B. Thus I 45 provide a squeegee A of a very desirable nature because the utility of the squeegee member 16 is greater than has been accomplished heretofore, in a simpler and more practical manner. The operator of my squeegee A may readily change 50 the position of the squeegee 16.

A further advantage of my squeegee A resides in making the members B and C, as well as the clamping member 23, out of aluminum or other light weight material. The parts of my squeegee 55 are all replaceable when they wear out or should they become damaged for any reason. Thus I provide a further advantage in my simplified squeegee A. It is also an advantage of my squeegee A in that the handle C may be removed 60 without disturbing the position of the squeegee strip 16 and the backing strip 20. This permits easier packing for shipment or storage of my squeegee.

My squeegee may be made also in the form 65 illustrated in Figure 8, wherein the holder portion B' is formed angular with a back angle member 24 projecting virtually at right angles from the flange 10', which provides an aligning shoulder for the squeegee strip 16 and the backing strip 20. In this construction the clamping bar 23' is slightly wider than the clamping bar 23, however, it is held to the flange 10' by the screws 22'.

It will be apparent that when the squeegee 70 strips 16 and 20 are in operative position that

either the series of holes 18 or the series of holes 19 will be exposed on the under side of the squeegee strip 16. These holes are equally spaced marginally from the edge 17 and one side of the same is closed by the backing strip 20, as illustrated in Figure 4. Thus the openings 18 or 19 provide pockets or wells which are adapted to collect the water or moisture which is squeegeed off of a surface by the edge 17. Thus the openings 18 or 19 act as retarders for the free flow 10 of liquid along the under side of the squeegee member 16 in operation. I have found that this is a material advantage of my squeegee A because it prevents free dripping of the water from the ends of the squeegee A in the use of the same. 15 Ordinarily moisture runs from the ends of the squeegee in its use and is apt to drip back onto the surface that has been squeegeed, whereas, in my device I find that this will not occur under the ordinary squeegee process and where the 20 surface squeegeed is not too wet.

It is apparent that the advantages of my squeegee A are material in accomplishing more desirable results and in providing a greater utility in a simple and practical manner.

I claim:

1. A squeegee comprising, a channel member having an upper wide longitudinally extending flange, a short longitudinally extending under flange, wide and narrow flexible squeegee members adapted to have one edge projecting from said wide flange and the other edge extending longitudinally in the recess of said channel between said wide and short longitudinal flanges, and a clamping means adapted to removably secure said squeegee members including a longitudinally extending floating bar on the under side of the same extending adjacent said short flange, and a series of screws extending through said wide flange and threadedly anchored in said bar. 40

2. A squeegee including, a squeegee member, means for supporting said member, and pocket means spaced from the squeegee edge formed in said squeegee member between said supporting means and the wiping edge of the squeegee for 45 containing liquid and retarding the free flow of liquid along said member.

3. The combination of, flexible replaceable squeegee means, clamping means for removably supporting said squeegee means including adjusting means to regulate the tension of said clamping means on said squeegee means, a series of liquid collecting pockets spaced from and positioned between said clamping means and the wiping edge of the squeegee in a portion of said 55 squeegee means extending along one side thereof, and a handle projecting from said clamping means for operative engagement of said squeegee.

4. The combination of a reversible, replaceable 60 squeegee member formed of flexible material, a series of pairs of openings extending parallelly along said squeegee member, a holder for supporting said squeegee member, and clamping means adapted to extend through one series of 65 said openings to hold said squeegee member in one position, the other series of openings positioned between said clamping member and the wiping edge of the squeegee providing water retarding wells along one side of said squeegee 70 member when held in this position, and the reverse taking place when the series of openings which form the wells act as the means of engagement for said clamping means.

5. The combination of, a flexible squeegee 75

member, a series of pairs of openings formed in the body of said squeegee member, clamping and holding means for engaging said squeegee member through one of said series of openings at a time, the other series of openings positioned between said clamping member and the wiping edge of the squeegee to form water retarding pockets, said openings being positioned in said squeegee member in a manner to permit either series to be engaged by said clamping and holding means so that the squeegee member may be reversible to permit either longitudinal edge thereof to be used as a squeegee.

6. A squeegee including, a flexible squeegee member, a series of pairs of openings equally spaced marginally of the longitudinal edges of

said member, and means for holding said squeegee member reversible by engagement in either of said series of openings, said holding means exposing the openings not engaged to provide water retarding wells.

7. A squeegee including, a channel-shaped member having substantially parallel side walls, one of said side walls being wider than the other side wall, a flexible squeegee, a clamping member oppositely disposed to said wider side wall to clamp said flexible squeegee thereagainst, and a base on said channel of sufficient width to space said squeegee from the shorter of said walls when clamped against the wider wall.
